UNITED STATES PATENT OFFICE.

ERNEST E. TUCKER, OF NEW YORK, N. Y.

OXYHYDROGEN STEAM GENERATOR.

Application filed April 17, 1922. Serial No. 553,828.

To all whom it may concern:

Be it known that I, ERNEST E. TUCKER, a citizen of the United States, and resident of New York, in the county of New York and State of New York, have invented certain new and useful Improvements in Oxyhydrogen Steam Generators, of which the following is a specification, reference being had therein to the accompanying drawing.

10 This invention relates to the utilization of the intense heat of the oxyhydrogen flame, or a flame resulting from burning a suitable combustible material, as hydrogen for example, and a suitable combustion supporting medium, as oxygen for example, properly blended together, in the production of steam or other vaporized liquid, and consists essentially in an apparatus or means and method of practically using such a flame for the described purpose, in a specially constructed boiler or generator.

15 The invention aims, therefore, as a chief object, to employ and apply one of the most powerful known sources of heat energy to make steam, and to provide practical means for doing this, a thing which has heretofore been considered impracticable owing to the great difficulty of controlling, directing and confining the oxyhydrogen flame in heating 20 a liquid.

The invention may further be described as consisting essentially in the injection of an oxyhydrogen flame, or the flame of some other suitable combustible material and suitable combustion supporting medium properly blended, under pressure into the combustion chamber of a generator, where it meets and operates upon water or other liquid to be vaporized, when the same is in 25 a finely-subdivided state, as spray or other atomized condition, the quantity of the injected flame being proportioned to the amount of the water or other liquid capable of being vaporized by the heat of combustion 30 released for the purpose; or in the reverse operation of injecting an atomized liquid against an oxyhydrogen flame.

Many obvious advantages will accrue from the use of such a method and means 35 for vaporizing the water and producing steam. Some that I may mention will be the elimination of the common separate combustion chamber and its appurtenant features, through the consolidation of the water-containing and combustion spaces

into a single unified structure in which the combustion area is greatly diminished in size; the absence, therefore, of large flues and tubular constructions and other expensive boiler absorption surfaces; the instant 40 generation of steam or superheated steam in unlimited quantities at any desired temperature directly at the feed pipe of the driven machinery or elsewhere; a perfect economy of all the forms of the energy of 45 combustion, except that lost by radiation; the regulation of speed or power by the regulation of the combustion material, with a corresponding economy of the energy of combustion.

The invention consists, furthermore, in various details and peculiarities in the construction, arrangement and combination of parts, substantially as will be hereinafter more fully described and claimed.

In the accompanying drawing illustrating my invention:

Figure 1 is a diagrammatic plan view of my improved oxyhydrogen steam generator.

Figure 2 is a cross-section of the same on 50 the line 2, 2, of Figure 1.

Figure 3 is an enlarged sectional detail of the main part of the oxyhydrogen blow-pipe for producing the flame.

Figure 4 is a cross-sectional view similar 55 to Figure 2 of a modified form of the invention.

Similar characters of reference designate like parts in all the different Figures of the drawing.

As stated, in order to instantly vaporize the liquid to an exceedingly high temperature, I use a combustible material and a combustion supporting medium properly blended together, from the flame of which an intense heat is supplied which quickly converts water into steam. As an example of combustible material I prefer hydrogen, which is a colorless, tasteless and inodorous gas, which burns in the air with a very pale 60 blue flame and an intense heat, the sole product of combustion being water, which is the protoxide of hydrogen. A mixture of two volumes of hydrogen and one of oxygen explodes violently when brought 65 into contact with a flame or the electric spark. As an example of combustion supporting medium I prefer oxygen, which is a colorless, odorless and tasteless gas, somewhat heavier than atmospheric air, and 70

which combines very easily with most of the elements and forms oxides. The act of combustion is so energetic in many cases as to evolve light and heat, the phenomena of combustion. Other specimens of combustible material and combustion supporting mediums may obviously be used, but these are believed to be the best, because they serve so effectually in the oxyhydrogen flame in the blowpipe, the principle and structure of which I employ in carrying my invention into practical use.

In a blowpipe a current of gas or air is driven through the flame of a lamp, candle or gas jet, to direct the flame upon a substance, in order to fuse or otherwise affect it, an intense heat being created by the rapid flow of oxygen and the concentration of the flame upon a small area. In the oxyhydrogen or compound blowpipe, oxygen and hydrogen, in the proportions necessary for their combination, propelled by hydrostatic or other pressure, and coming from separate reservoirs, are made to form a united current in a capillary orifice at the moment when they are kindled. The high degree of heat fuses or vaporizes many substances that are refractory at lower temperatures, consuming the diamond for example, cutting steel and iron, etc. My purpose is to thereby vaporize water or other liquid.

The diagrammatic plan view of Figure 1 shows a form of boiler in which the oxyhydrogen flame impinges on water (or water meets the flame) to vaporize the same and produce steam, the water being in an atomized condition, that is, being in the form of spray or small droplets. Essentially the boiler consists of a perforated shell, through the perforations of which the water is forced under pressure into the interior of the shell, where it is met by the vaporizing flame that also enters the interior of the shell through the wall thereof at one or more points. The perforations or apertures are arranged radially around the shell and directed toward the flame, and they are so proportioned that the exact amount of liquid capable of being vaporized by the heat may be injected, and also the gas entrance allows the exact amount of combustible material and combustion supporting medium for perfect combustion to be introduced. Hence the heat-absorbing surface of the boiler instead of being a large metal surface is made up of the liquid to be vaporized which is in the form of a surface of finely-divided particles of water.

18 denotes the boiler shell, having a plurality of perforations 6 over its surface, as numerously as may be found desirable, one end 18^a of shell 18 being preferably semi-globular or dome-shaped at the center of which the blowpipe is seated. These perforations

may be arranged radially or fanwise as shown. The shell 18 is located within a water jacket or chamber 7 having outer wall or casing 2, which chamber receives water under pressure through pipe 3. The water in chamber 7 is forced through the needle holes or perforations 6 to form needle jets or fine sprays of water within shell 18, so that the water here will offer a heat-absorbing surface and will be in an atomized or finely subdivided condition and ready to be attacked by the combustible gas. Shell 18 has a refractory or noncombustible lining 5, which not only lines the same, but extends as a cylinder 4 beyond the shell, or if the shell itself has a cylindrical extension the lining may extend throughout the latter, and said part 4 of the lining or of the shell proper is provided with churning spirals 8 to act on the water in rotating and mixing the same thoroughly with the products of combustion. The said combustible material and combustion supporting medium yield in combustion a water vapor, or a liquid the same as the liquid to be vaporized, so that it will blend perfectly with such vaporized liquid and will thus assure the utilization of all the heat units of combustion, and hence as it leaves no non-liquefying residue it will not interfere with recondensation, and so that if used in torpedoes and under-water craft, it will on escaping blend and condense completely in the sea water and leave no bubbles, or a minimum of bubbles in its trail, especially if escaping through numerous tubes of fine calibre cooled by the sea water. The lining for the generator is a material capable of resisting the intense heat, reaching as far as the flame in case of an accident such as cutting off the water supply could reach with fusing effect. The spiral ridges 8 or other irregularities of surface act to throw the liquid to the cavity in broken masses, and also act so that the current of gas will be driven against the liquid with the same effect.

1, 1, denote steel bottles, tanks, reservoirs or other containing vessels for holding water under pressure, one of said bottles having a pipe 3 which runs therefrom to the water chamber 7 and delivers water thereto under pressure, so that it may pass through the openings 6 in small streams into the boiler shell 18. A pump 10 is arranged in connection with a pipe line 11, which communicates with the two bottles or tanks 1, 1, and also a pipe 9 leads from the boiler to the pump so as to pick up and carry to the pump any unvaporized water in the generator. The pump 10 may be connected with any suitable water supply, at the same time that it is connected with the tanks 1, 1, or otherwise, as preferred or found most practicable; but the chief point about the flow of the water or other liquid to the generator is that

it should be under pressure, to enable it to be atomized or divided within the interior of the boiler shell where the combustion is taking place. Pipes lead from the water tanks 1 to the gas tanks 12 and 13 so that water pressure may be used to force the gas to the burner under pressure.

12, 12, denote hydrogen tanks or containers, and 13 an oxygen container. Tanks 12, 10 12, connect by a pipe 14 with the nozzle 19 just inside boiler shell 18, see Figure 3, and tank 13 connects by pipe 15 with the nozzle 20 just inside boiler shell 18; the nozzles 19 and 20 being only a short distance from each 15 other so that the streams of oxygen and of hydrogen gas may commingle with each other at this point. An electrical ignition means is located adjacent to the nozzles 19 and 20 and includes the electrodes 22 and 23, 20 said electrode 22 being at the end of a wire 16 carried in a tube 24, and said electrode 23 being at the end of a wire 17 carried in a tube 25, these carriers 24 and 25 being supported in a refractory wall 21 for the retention 25 of heat at the ignition point. Obviously the wires 16 and 17 will connect with an ignition coil (not shown). A spark will jump from the electrode points 22 and 23 at the proper time to ignite the gases, and the 30 oxyhydrogen flame in its blowpipe action will be directed against the water converting the same instantly into steam and liberating immense quantities of thermic, electric and chemic energy in contact with the particles 35 of water. These poles that give the ignition spark are kept from fusing by being placed, as stated, one within the current of hydrogen or other combustible material, and the other within the current of oxygen or other combustion 40 supporting medium, before these currents are blended and thus are kept cool by the currents, and the spark will cross the area of the blending to effect ignition. Instead of this ignition system others may be 45 used, as for example a catalyzer which automatically causes ignition on contact.

It may be remarked that the effect of the high degree of heat upon the water is not only to vaporize the same, but owing to the kind of fuel which is a mixture of hydrogen and oxygen there will be a blending together of the actual materials in a state of combustion. It is not a mere mixing of the products of combustion with 55 water in a steam generator, such a mixture as would be only temporary and would allow gases to rise to the surface of the liquid; but it is a totally different thing from this, in that in my boiler the product 60 of combustion is water itself and can not only mix with but actually blend with the water of the generator, in which case the absorption of heat would be capable of being complete.

65 In Figure 4 I show a modification in the

structure of the boiler, there being circular or curved ribs 30 formed in parallel series in the wall of the shell with the rows of perforations 6 between them. These ribs enlarge the space and give opportunity for the 70 expansion of the steam, as well as the more extensive distribution of the water in the combustion space.

I shall expect hereafter to develop and apply for Letters Patent upon all needful 75 equipment in the form of many kinds of apparatus for taking care of a multitude of mechanical and operating problems and to this end will devise and offer many forms of means for blending the gases; for converting a liquid into the smallest practicable 80 particles for exposure to the flame; for injection of the ignited gases into contact with the atomized liquid in the most advantageous way for vaporizing; for suitable 85 effective ignition means; for protecting all the parts of the mechanism from fusing in consequence of the extreme temperatures employed; for a unit regulation of the supply of each gas and liquid; for a pressure 90 system which will cause each element to be under the proper pressure for effective results, hydrostatic pressure or otherwise; for a systematic regulation of the 95 whole.

The use of the described means and method for generating steam will be found to have a great number of commercial advantages and benefits. Against a possible 100 higher cost of fuel must be weighed the ease of handling and transporting this fuel, the simplicity of transforming the energy of a waterfall or other natural power into stored energy of this character, the saving in space and weight and labor, and in fine 105 the simplicity of the process at all points. My invention is applicable to any form of engine; that is, in internal combustion engines, like gasoline engines, or in connection with coal burning engines. In cases 110

where it is desirable to produce steam immediately, as in fire engines, it has a large field, especially where steam is needed for short periods. In connection with coal burning furnaces it may be used as an accessory steam generator to operate the engines while steam is being raised or while a boiler is being repaired. The use of steam in aviation has many advocates, and a means is hereby supplied to produce such steam within the weight and space limits of aviation. Its use in general commerce may be compared with the development of cheap 120 methods of producing the fuel.

I conceive also that in the development of 125 this invention and its application to manifold uses it may be necessary to provide for regulating the pressure system automatically at a given point and for varying the point. I expect also to detect any sur-

plus gas or water and provide for automatic regulation of the same; also to employ pumping means acting proportionately on the gas and water; to employ means for adjusting the pressure when the gases are supplied in condensed form; for valve means and other devices for connecting and disconnecting the gas compression and water tanks; to offer means for using suitable explosive action in further atomizing the liquid; to provide manifold condensation means.

Having thus described my invention, what I claim as new and desire to secure by Letters Patent is:

1. In a device for generating motive fluid, the combination with a steam generator having means consisting essentially of a perforated shell for spraying water, of an oxyhydrogen blowpipe arranged to apply its heat to the sprayed water to vaporize the same, the product of combustion being water which commingles with the vaporized water.
2. In an apparatus for the generation of motive fluid by injecting a combustible fluid and a combustion supporting medium into contact with a liquid to be vaporized, a combined combustion chamber and steam space having perforations through which the liquid to be vaporized enters the combustion space.
3. In an apparatus for the generation of motive fluid by injecting a liquid to be vaporized as streams of finely divided or atomized spray into contact with the fuel in a state of combustion, a combined combustion chamber and steam space having perforations which have the function of finely subdividing the liquid to be vaporized in order that the same may act as an absorbing surface.

4. In an apparatus for the generation of motive fluid by injecting a combustible fluid and a combustion supporting medium into contact with a liquid to be vaporized, a shell having perforations through which the liquid to be vaporized enters the combustion space, a liquid chamber surrounding said shell, an oxyhydrogen blowpipe in one end of the shell, all arranged so that the finely divided particles of liquid passing through the perforations in the shell may be brought into contact with the oxyhydrogen flame.

5. A method to produce steam or superheated steam or other vapor instantaneously, and utilizing the chemical and electrical energy of combustion to force a rapid absorption of heat, which consists first vaporizing the stream of liquid and then injecting a combination of combustible fluid and combustion supporting medium in a state of combustion against the aforesaid stream of liquid which is being vaporized while the same is in an atomized state so as to cause the liberation of thermic electric and chemic

energy in intimate contact with the finely divided particles of the liquid to be vaporized.

6. In an apparatus for generating motive fluid by means of a flame driven against streams of finely divided particles of the liquid to be vaporized, a generator shell having an arrangement of inlets for such liquid whereby the streams entering will be sprayed fanwise and automatically separated into small particles proportionately to the force introducing the water and flame.

7. In an apparatus for generating motive fluid by means of flame driven against streams of finely divided particles of the liquid to be vaporized, a generator shell having radial inlets for such liquid which subdivide the entering streams radially.

8. In an apparatus for generating a motive fluid by means of flame driven against fanlike divided streams of liquid to be vaporized, a generator having an arrangement of inlets for such streams so that the finely divided particles will be exposed most effectively to the heat of combustion, said inlets being in parallel longitudinal rows and arranged radially around and directed towards the flame.

9. In an apparatus for generating motive fluid by means of flame driven against finely divided streams of liquid to be vaporized, a generator having an aperture for the injection of a combustible fluid and a combustion supporting medium, such that the flame thereof will be directed toward the convergence of the streams of liquid to be vaporized, said generator having also radial apertures for introducing the streams readily toward the axis of the generator.

10. In an apparatus for generating motive fluid by means of the injection of liquid to be vaporized, together with a combustible liquid and a combustion supporting medium, a generator shell having apertures so proportioned in size that the exact amount of combustible material and combustion supporting medium for perfect combustion and the exact amount of liquid capable of being vaporized by the heat so developed may be injected.

11. In an apparatus for generating motive fluid, the combination with a perforated combustion chamber and oxyhydrogen flame producing means, all arranged so that the relatively small combustion chamber has a perforated surface which will have the function of finely subdividing particles of liquid in order that they may have the function of an absorbing surface, and a device for increasing the absorbing surface of any residue of such liquid not at first vaporized and sinking to the bottom of the generator, and driven along by the current of gases, consisting of spiral ridges or other irregularities of surface whose action will be to throw

such liquid to the cavity of the generator in broken masses, and such that the current of gases will be driven against the liquid with the same effect.

- 5 12. In an apparatus for generating motive fluid by injecting in combination a liquid to be vaporized, a combustible material and a combustion supporting medium, said combustible material and combustion supporting medium on combustion yielding the same substance as the liquid to be vaporized, a relatively small combustion space and a liquid chamber surrounding the said space.
- 10 13. In an apparatus for generating motive fluid by the injection in contact with a stream of liquid to be vaporized of a stream of combustible material and combustion supporting medium in state of combustion, which burns at high temperature, a system 15 of ignition consisting of an electric spark from poles which are kept from fusing by being placed one within the current of combustible material and the other within the current of combustion supporting medium 20 before these are blended, so kept cool by the currents; and so that the spark will cross the area of the blending to effect ignition.
- 25 14. In an apparatus for generating motive fluid by the injection against a stream of volatile liquid of a stream of burning ma.

30 terial that burns at intense heat, nozzles for the apertures, liquid channels, and a lining for the generator of material capable of resisting the intense heat, said lining reaching as far as the flame.

35

15 15. In an apparatus for generating motive fluid by injecting against a stream of volatile liquid a stream of burning material that burns at high temperature, and supplied with apertures for inlet of such volatile 40 liquid, a water jacket surrounding the generator and communicating with the apertures so that heat radiating from the generator may be absorbed and become effective in raising the temperature of the volatile liquid 45 to the boiling point.

16. In an apparatus for generating motive fluid in which combustion chamber and generating chamber are combined in one, means for injecting volatile liquid, combustible material and combustion supporting medium in combination, and a device for producing the required pressure for such injection consisting of a pipe leading from the generating chamber to a pump for supplying the added 50 pressure, and supplied with means by which the speed of the injection may be regulated.

55 In testimony whereof, I hereunto affix my signature.

ERNEST E. TUCKER.
